ELECTRICALLY ACTUATED PUMP

John W. Dickey, Millard M. Henry, and Theodore K. Rigen, Elmira, N. Y., assignors to Bendix Aviation Corporation, Elmira Heights, N. Y., a corporation of Delaware

Application February 11, 1946, Serial No. 646,950

4 Claims. (Cl. 172—126)

1

The present invention relates to reciprocating electrical motors and more particularly to motors for actuating pumps to automatically maintain a supply of liquid under substantially uniform pressure irrespective of the quantity required, such as fuel pumps for internal combustion engines.

It is an object of the present invention to provide a novel pump motor of the above type which is efficient and reliable in operation while being simple and economical in construction.

It is another object to provide such a device which is so constructed that it requires very little electrical energy for its operation.

It is another object to provide such a device incorporating a reciprocating piston of magnetic material in which the actuation of the piston is controlled magnetically by means of flux which traverses the piston.

It is another object to provide such a device incorporating contacts for controlling the actuation of the piston with means for preventing burning or erosion of the contacts.

It is another object to provide such a device in which the control contacts are actuated by a permanent magnet, and the piston is arranged to move into and out of the field of the magnet to thereby vary the reluctance of the flux circuit.

It is another object to provide such a device in which the means for controlling the contacts is substantially balanced so as to be unaffected by translational forces, and is actuated solely by magnetic force in opening and closing the contacts.

Further objects and advantages will be apparent from the following description taken in connection with the accompanying drawings in which:

Fig. 1 is a vertical substantially mid-sectional view of one preferred embodiment of the invention, the electrical circuit connections thereof being shown diagrammatically;

Fig. 2 is a section taken substantially on the line 2—2 of Fig. 1;

Fig. 3 is a sectional detail showing the magnetic means for controlling the contacts, taken substantially on the line 3—3 of Fig. 2;

Fig. 4 is a sectional detail taken substantially on the line 4—4 of Fig. 2, the flux circuit of the control magnet being indicated by dotted lines;

Fig. 5 is a view similar to Fig. 2 of an embodiment of the invention showing a contact controlling rocker actuated by a substantially cubical permanent magnet; and

Fig. 6 is a view similar to Fig. 5 of an embodiment of the invention incorporating a spring type

2

of hinge for the contact controlling mechanism.

In Fig. 1 of the drawing, there is illustrated a cylindrical pump casing 1 having a closure cap 2 fixed in its upper end as by brazing or welding, and a removable cap 3 fitted on its lower end with an interposed gasket 4, providing a fluid-tight joint. The casing member 1 is preferably composed of magnetically permeable material such as soft iron, and a partition member 5 of similar material is fixed therein by suitable means such as copper welding, the position of the partition being preferably determined by an internal rib 6 formed in the casing. A pump cylinder 7 of non-magnetic material such as brass or stainless steel is mounted at its ends in the cap 2 and the partition 5 respectively, said cylinder having preferably a light press fit in the cap and partition, and the joints being rendered fluid-tight by suitable means such as copper welding.

20 The annular chamber formed by the casing 1, cap 2, partition 5, and cylinder 7 is preferably evacuated or charged with an atmosphere of an inert gas in order to prolong the life of the electrical elements housed therein.

25 The partition 5 is provided with an upwardly extending sleeve portion 8 providing a lower magnetic pole piece, and an upper pole piece is provided by a collar member 9 of magnetic material having a press fit in the casing 1 and closely surrounding the cylinder 7. An electromagnetic coil 11 occupies the space between the pole pieces 8 and 9, whereby when the coil is energized, a magnetic circuit is provided comprising pole piece 8, partition 5, casing 1, pole piece 9, and the gap between the pole pieces 8 and 9 which is bridged by the pump cylinder 7.

The partition 5 is provided with a downwardly extending sleeve portion 12 which is threaded interiorly to receive a threaded inlet valve member 13. The member 13 is provided with a vertical passage 14 having an enlarged valve chamber 15 extending into the lower end of the cylinder 7. A valve seat 16 is formed at the bottom of the chamber 15, and a check valve member 17 is slidably mounted in the chamber and normally held in engagement with the seat 16 by means of a valve spring 18 which is retained in the chamber by means of a thimble 19 fixed in the upper end thereof as indicated at 21.

50 The inlet member 13 is provided with a plurality of radial passages 22 communicating with the interior passage 14 and opening out into the space surrounding the inlet member. The inlet member is also provided with a cylindrical enlargement 23 having a shoulder 24; and a screen

member 25 is arranged to seat at its lower end on the enlargement 23 and at its upper end on a packing ring 26 pressed on the partition member 5, said screen member being maintained in position by the shoulder 24 of the inlet member. The lower end of the inlet member is tapped as shown at 27 for the reception of a stud 28 which clamps the cap 3 against the lower end of the casing 1.

A cylindrical piston 29 of magnetic material is slidably mounted in the cylinder 7 and is provided with a passage 31 therethrough which is narrowed at its upper end to provide a shoulder 32. Said shoulder provides a seat for the upper end of a spring 33 which rests at its lower end on the thimble 39 whereby the spring urges the piston toward the upper end of the cylinder 7. A valve seat 34 is formed on the upper end of the piston 29, and a valve member 35 is yieldingly pressed against the seat by a spring 36 which is retained by a thimble 37 fixed to the upper end of the piston as indicated at 38.

An inlet pipe fitting 39 is fixedly mounted in the lower part of the casing 1 in any suitable manner and arranged to receive a tube 41 communicating with a source of liquid to be pumped. A baffle 42 is preferably fixed to the inside of the casing 1 in order to deflect the entering liquid downwardly, and peripherally, and thereby assist the deposit of any suspended foreign material in the bottom cap 3 of the casing. An outlet pipe fitting 43 is fixed in the upper end of the cylinder 7 with any suitable form of fluid-tight connection and is arranged to receive a tube 44 communicating with the receptacle to be supplied by the pump.

Means for periodically energizing the electromagnet 11 so as to cause actuation of the pump plunger 29 is provided comprising a battery 45 grounded at 46 and connected through a switch 47 and conductor 48 to a binding post 49 mounted in the casing 1 and suitably insulated therefrom. A conductor 51 connects the binding post to one terminal of the electromagnet 11, and the other terminal of the electromagnet is connected by a conductor 52 to a contact 53 mounted on a bracket 54 but insulated therefrom as indicated at 55. A movable contact 56 is mounted on a spring arm 57 (Fig. 2) fixed as indicated at 58 to a rocker 59 rotatably mounted on a pin 61 projecting upwardly from the upper pole piece member 9. The rocker and consequently the contact 56 are preferably electrically grounded by suitable means such as a flexible connection 60. A block 62 of permanently magnetized material is attached to the rocker 59 as by means of a clamping screw 63. The block 62 is shaped to conform to the adjacent exterior surface of the cylinder 7, and is so magnetized as to present one pole to said cylinder, while the opposite pole of the magnet faces the interior of the casing 1. A spacer 64 of non-magnetic material is suitably affixed to the interior of the casing 1 in position to limit the swinging movement of the magnet 62 and prevent its engagement with the interior of the casing. A weight member 65 is preferably attached to or formed as a part of the rocker 59 in position to balance the weight of the block magnet 62, and also to serve as an abutment for the contact spring arm 57 and thereby provide a positive means for disengaging the movable contact 56 from the stationary contact 53.

When the parts are in idle position, the spring 33 holds the piston 29 in the upper end of the cylinder 7 with the thimble 37 in engagement

with the lower end of the outlet fitting 43 or with an interposed cushioning block 66 of suitable material if deemed desirable. Since at this time the upper end of the piston is in registry with the permanent magnet 62, the attraction of the magnet for the piston causes the magnet to be held against the surface of the cylinder 7 so that contact 56 is pressed into engagement with contact 53 as shown in Fig. 2. When the switch 47 is closed to place the pump in operation, current from the battery 45 traverses the electromagnet 11 and contacts 53, 56, returning by way of the ground, so that the electromagnet is energized and draws the piston 29 downwardly. The liquid in the lower end of the cylinder 7 is thereby forced up through the piston 29 and check valve 35, 34 into the upper end of the cylinder. When the upper end of the piston passes out of the field of the permanent magnet 62, said magnet is no longer attracted toward the cylinder 7, and its attraction for the casing 1 causes it to move outwardly into engagement with the spacer 64, thus moving contact 56 out of engagement with contact 53, deenergizing the electromagnet. The spring 33 then moves the piston 29 upwardly, ejecting the liquid trapped above the piston through the outlet conduit 44, and drawing a charge of liquid into the lower end of the cylinder through the check valve 17, 16. As soon as the upper end of the piston approaches the permanent magnet 62, said magnet again moves the rocker 59 to close contacts 56, 53, and repeat the operation which continues as long as the switch 47 is closed and there is a demand for fluid to be supplied through the conduit 44. When the receptacle to be supplied is full, the back pressure of the liquid prevents the piston from rising, so that thereafter the actuation of the piston occurs only as and when there is a demand for the fluid to be supplied.

In order to reduce sparking at the contacts 53, 56, a cylinder 68 of electrically conductive material such as copper is preferably placed on the pump cylinder 7 between the pole pieces 8 and 9. Burning or erosion of said contacts is further inhibited by the inert atmosphere within the upper portion of the casing 1, whereby efficient operation of the pump over long periods of time is assured.

In Fig. 5 of the drawing, there is illustrated a modification of the control contact actuating means in which the permanent magnet is in the form of a solid block which requires no machining. As here shown, rocker 71 pivoted at 72 has a pole piece 73 conforming to the exterior of the cylinder 7, and a permanent magnet 74 of substantially cubical shape is clamped to the rocker by means of studs 75 and 76. An arm 77 fixed to the rocker 71 has attached thereto at 78 a contact spring arm 79 which carries at its free end the movable contact 81. A spring 82, also attached to the arm 77 by the rivet 78, bears against the interior of the casing 1 and tends to move the contact 81 away from the fixed contact 53. The remaining parts of the structure here shown are the same as in the first embodiment of the invention described, and are similarly numbered. The operation is the same as previously set forth except that the arm 77 serves to positively break the contacts 81, 53 when the spring 82 withdraws the pole shoe 73 from the cylinder 7.

In Fig. 6 of the drawing, a control magnet 91 is mounted on a flexible hinge member 92 anchored at 93 to the upper pole member 9 of

the electromagnet 11, and a contact 94 is mounted on a spring arm 95 also fixed to the permanent magnet 91 in position to engage the fixed contact 53. A block 96 of magnetic material such as iron is fixed on the inside of the casing 1 in position to draw the magnet 91 away from cylinder 7, a pad 97 of suitable non-magnetic material such as fibre being cemented on the block 96 to form a backstop for the magnet, and limit the opening of contacts 94, 53. The remaining parts are the same as shown in Fig. 1 and are similarly numbered, and the operation of the device is substantially the same except that in this case the movement of the permanent magnet 91 in opening and closing the contacts 94, 53, 15 is permitted by flexure of the hinge 92 instead of by pivotal movement of a rocker.

Although certain embodiments of the invention have been shown and described in detail, it will be understood that other embodiments are possible and that changes may be made in the design and arrangement of the parts without departing from the spirit of the invention as defined in the claims appended hereto.

What is claimed is:

1. In an electrically actuated pump, a cylinder of non-magnetic material, a hollow piston of magnetic material slidable therein, a spring arranged to move the piston toward the discharge end of the cylinder, electromagnetic means adapted when energized to move the piston toward the inlet end of the cylinder, and contacts for controlling the energization of the electromagnetic means, one of said contacts being movable; means for moving said contact including a permanent magnet and mounting means therefor permitting movement thereof toward and away from the cylinder, the permanent magnet being so located near the discharge end of the cylinder that the piston on its discharge stroke enters the field of the magnet and thereby causes the magnet to move in a direction to bring the movable contact into engagement with the cooperating contact; and magnetic means in the field of the permanent magnet so located that the attraction of the permanent magnet therefor causes the magnet to move in a direction to separate the movable contact from its cooperating contact when the piston is withdrawn from the influence of the magnet.

2. An electrically actuated pump as set forth in claim 1 including further, a casing of magnetic material enclosing and sealing the actuating and controlling means for the piston in inert atmosphere while constituting means for conducting the flux of the electromagnet and the permanent magnet.

3. In an electrically actuated pump, a non-magnetic cylinder, a magnetic piston reciprocable therein, an electromagnet for moving the piston toward the inlet end of the cylinder, means for energizing the electromagnet including a pair of contacts, means for opening and closing the contacts including a permanent magnet located adjacent the discharge end of the cylinder, a spring for moving the piston into the field of the permanent magnet whereby the mutual attraction moves the permanent magnet to close the contacts, and magnetic means adjacent the permanent magnet for moving it to open the contacts when the piston is withdrawn by the electromagnet from the field of the permanent magnet.

4. An electrically actuated pump as set forth in claim 3 including further, non-magnetic means for spacing the permanent magnet from the magnetic means for opening the contacts, so as to cause the effect of the piston on the permanent magnet to preponderate when the piston enters the field of the permanent magnet.
